GRINDING MACHINE

Ervin S. Mummert, Hanover, Pa., assignor to
Mummert-Dixon Company, Hanover, Pa., a
corporation of Pennsylvania

Application July 18, 1936, Serial No. 91,257

3 Claims. (Cl. 51—99)

This invention relates to grinding machines and more particularly to the type of grinding machines known as swing frame grinders in which the machine is suspended from an overhead support by a flexible element such as a chain, cable or the like.

An object of the invention is to provide an improved swing frame grinding machine which is suspended in such a way that both longitudinal and lateral adjustments may be made, so that the machine will be perfectly balanced without the necessity of employing any additional balancing weights or the like.

Another object of the invention is to provide an improved swing frame grinding machine having its suspending arm or hanger adjustably mounted on a supplementary frame, which latter in turn is adjustably mounted on the main frame of the machine.

Another object of the invention is to provide an improved swing frame grinding machine of the character mentioned, which is simple in construction, and reliable and exact in function under all conditions of service.

The invention also comprises certain new and useful improvements in the construction, arrangement and combination of the several parts of which it is composed, as will be hereinafter more fully described and claimed.

In the accompanying drawings:—

Figure 1 is a plan of a swing frame grinding machine constructed according to the present invention;

Fig. 2 is a side elevation of the structure shown in Fig. 1;

Fig. 3 is a vertical transverse section taken on the line 3—3 of Fig. 2;

Fig. 4 is a similar section taken on the line 4—4 of Fig. 2; and

Fig. 5 is a similar section taken on the line 5—5 of Fig. 2.

Referring to the drawings, the improved grinding machine comprises a main supporting frame 11, which is preferably though not necessarily constructed of a suitable length of heavy pipe or tubing.

Mounted on one end of the main supporting frame 11 is a wheel head frame 12, which supports a grinding wheel 13.

Mounted on the opposite end of the main supporting frame 11 is a motor carrying frame 14, upon which is mounted an electric motor 15.

The shaft of the electric motor 15 is provided with a pulley 16 having grooves formed therein for a plurality of belts 17. The belts 17 en-

circle a similarly formed pulley on the shaft 18 of the grinding wheel 13, said pulley being covered by a suitable hood or guard 19, as shown in Fig. 1.

The grinding wheel 13 is also partly covered by a hood or guard 20 which is fastened to the wheel head frame 12 by means of bolts 21.

Projecting from the grinding wheel hood 20 are handles 22 for the operator of the machine.

In the specific type of machine herein shown and described, the grinding wheel 13 is shown disposed substantially in alinement with the end of the main supporting frame 11, the frame 12 of said grinding wheel being offset at one end in the manner shown in Fig. 1, so as to provide a support for the driving pulley (not shown) of the grinding wheel 13.

Extending lengthwise of the machine and covering the driving belts 17, is a cover 23 which is preferably formed of sheet metal.

The motor 15 is mounted on a suitable platform 24 which is supported by the motor carrying frame 14 as shown in Fig. 2.

Also supported by the motor carrying frame 14 is a bracket 25 having a boss 26 for receiving one end of an auxiliary or supplementary supporting frame 27.

The supplementary supporting frame 27 comprises a tube or section of heavy pipe which is somewhat shorter in length than the length of the main supporting frame 11.

The outer end of the supplementary supporting frame 27 is secured to a suitable connector or bracket 28.

The connector or bracket 28 is formed with a main body portion 29 which snugly fits the main supporting frame 11. Extending upwardly from the main body portion 29 of the connector or bracket 28 is an arm, the upper end of which is formed with a slot 30 through which is inserted the shank of a bolt 31 which is employed for securing the outer free end of the supplementary supporting frame 27 to the connector or bracket 28.

The main body portion 29 of the connector or bracket 28 is rigidly secured to the main supporting frame 11 by means of set screws 32 (see Fig. 5).

The bracket 25 which supports the inner end of the supplementary supporting frame 27 is adjustably mounted on the motor carrying frame 14 for sliding movement transversely of the machine. For this purpose the base of the bracket 25 is formed with slots 33, as shown in Fig. 1, for the reception of the shanks of bolts 34.

Loosely mounted on the supplementary supporting frame 27, is a bearing 36, for a suspending arm or hanger 37.

- The bearing 36 is retained in position against longitudinal movement with respect to the supplementary supporting frame 27 by means of collars 38. The collars in turn are rigidly secured to the supplementary supporting frame 27 by means of set screws 39.
- 10 The lower end of the suspending arm or hanger 37 is pivotally connected to the bearing 36 by means of a pin 40 which is carried by the bearing 36 in the manner clearly shown in Fig. 4. The pin 40 is transversely disposed so that the hanger arm 37 is free to swing in a direction longitudinally of the machine, and since the bearing 36 is loosely mounted on the supplementary supporting frame 27, said bearing and the suspending arm or hanger 37 pivotally connected thereto, are free to swing in a direction at right angles to the longitudinal swinging movement which can be partaken of only by the suspending arm or hanger 37.

As shown in Fig. 4, the lower end of the suspending arm or hanger 37 is connected to the bearing 36 at a point offset to the main supporting frame 11 of the machine.

The upper end of the suspending arm or hanger 37 is laterally disposed with respect to the main body portion thereof, and said upper end carries an eye 41 for the reception of a hook or other device (not shown) on the lower end of a chain or cable from which the machine is adapted to be suspended. In order that the machine 35 can be moved in all directions, the eye 41 is loosely connected to the upper end of the suspending arm or hanger 37 by a swivel joint of any approved type.

When the machine is suspended by the arm or hanger 37, it is adapted to be evenly balanced, and in order to obtain such balance after the parts have been assembled, the bracket 25, the connector bracket 28, and the hanger bearing 36 are shifted until the entire machine is uniformly balanced, it being assumed that the machine is suspended from a suitable flexible element, as has been heretofore described, which is connected to the eye 41 of the arm 37.

When this adjustment of the above elements has been effected, the bolts 31 and 34 and set screws 39 are tightened, thereby retaining the movable parts of the machine relatively fixed, so that the machine will remain in proper balance when put into use.

55 In order to obtain correct balance of the machine it was necessary to provide means for shifting the position of the suspending arm or hanger 37 with respect to the main supporting frame 11 of the machine, and in order to effect such shifting of the hanger 37 it has been necessary to pivotally mount said hanger on an auxiliary or supplementary supporting frame which latter can also be shifted with respect to the main frame.

The transverse balance of the machine is effected by moving bracket 25 and the connector 28 in such a way that the supplementary supporting frame is shifted transversely with respect to the main supporting frame 11. The longitudinal balance is obtained by shifting the position of the hanger bearing 36 inwardly or outwardly of the supplementary supporting frame 27. In this way both transverse and longitudinal balance of the machine can be readily obtained without the use of any additional balancing weights.

Having thus described my invention, what I claim is:—

1. A grinding machine comprising an elongated supporting frame with a power unit at one end, a grinding tool at the other end, driving connections between the power unit and the grinding tool, a supplementary supporting frame superposed with respect to the main supporting frame, means for shifting the relative position of the supplementary supporting frame laterally with respect to the main supporting frame, a hanger, means for pivotally supporting said hanger on the supplementary supporting frame, and means for adjusting the hanger supporting means longitudinally with respect to the supplementary supporting frame whereby to balance the entire machine when the same is supported from said hanger.

2. In a grinding machine, an elongated main frame, a motor supported by said frame at one end, a grinding tool supported by said frame at the other end, a driving connection between said motor and said grinding tool, a supplementary frame, adjustable means connecting one end of said supplementary frame with said main frame at the motor end thereof, a bracket rotatably mounted on an intermediate portion of said main frame, means for adjustably connecting the other end of the supplementary frame with said bracket, a hanger, and means constituting a universal joint for connecting the hanger with said supplementary frame.

3. A grinding machine comprising a main supporting frame, a motor mounted on one end of said main frame, a grinding tool mounted on the other end of said main frame, driving connections between the motor and the grinding tool, a supplementary supporting frame paralleling the main frame and disposed in a plane above the main frame, means for adjustably connecting each end of said supplementary supporting frame to said main frame whereby the relative position of said supplementary supporting frame with respect to the main frame can be shifted, a bearing loosely mounted on said supplementary supporting frame for rotary movements transversely with respect to said supplementary supporting frame, and a hanger pivotally connected to said bearing and adapted to swing in directions at right angles to the transverse rotary movements of said bearing.

ERVIN S. MUMMERT.
